UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, A CORPORATION OF MASSACHUSETTS.

APPARATUS FOR FORMING HOLLOW ARTICLES BY DIES.

1,156,972.

Specification of Letters Patent.

Patented Oct. 19, 1915.

Application filed December 28, 1914. Serial No. 879,839.

To all whom it may concern:

Be it known that I, HJALMAR G. CARLSON, a citizen of the United States, residing at Worcester, in the county of Worcester and State of Massachusetts, have invented 5 a new and useful Apparatus for Forming Hollow Articles by Dies, of which the following is a specification.

This invention relates to an apparatus 10 for forming articles from sheet metal by means of dies.

The principal objects of the invention are to provide for eliminating the reheating, or annealing process, heretofore necessarily 15 employed, in drawing out sheet metal blanks into the form of hollow tubular or polygonal parts; to provide an arrangement of dies by which the reheating and annealing steps are avoided; to provide an arrangement of 20 dies by which a plurality of sets of dies can be mounted on one die bed and operated simultaneously so as to multiply the output and to provide an arrangement whereby with each reciprocation of the punch block, 25 four operations are performed instead of one as heretofore.

The invention also involves improvements in combinations of parts and details of construction as will appear herein.

30 Reference is to be had to the accompanying drawing in which,

Figure 1 is a central, vertical, sectional view of a die bed, punch block, and set of dies connected therewith, arranged in accordance with this invention; Fig. 2 is a 35 plan of the die bed and dies thereon showing the die punches in transverse section; Fig. 3 is a plan of the reducing die; Fig. 4 is a plan of the finishing die; Fig. 5 is a perspective 40 view of the cup-shaped blank; and Fig. 6 is a similar view of the product.

This invention relates to that class of work in which sheet metal blanks are cut out to a convenient shape and then cupped 45 and finally elongated and shaped for the purpose of producing hollow articles, such as shells and the like, of polygonal or even cylindrical form, but of a length considerably greater than that of the first cupped 50 out blank. Heretofore, so far as I am aware, articles of this kind have been produced by a series of dieing operations. A special set of dies has been necessary for each operation and consequently a special 55 machine. This necessitated the perform-

ance of these operations, one at a time, and the cooling of the blanks between each operation and the subsequent one. As it was necessary to have the blank in as soft a condition as possible in order that each operation might be performed efficiently, the blanks were put in an oven and reheated just before each operation. This necessarily added materially to the expense of the whole procedure and necessitated the handling of 60 the blanks in a certain definite manner. If there was any long interruption in the series of operations, an additional heating had to be given to the blanks.

Another difficulty which has interfered 70 with the speeding up of these operations, has been the fact that so far as I am aware, it has always been impossible to carry out these operations on a press having a plurality of sets of dies. This was due to the fact 75 that each die bed was made so that the die which it carried could be clamped thereon or released so that it could be replaced, but so that it always occupied the same position on the bed. The parts were set up in the 80 proper position by placing the previously formed article on the end of the punch and bringing the punch down into the female die and then shifting the die bed until it was brought to a perfect center with respect to 85 the punch. Obviously, this operation could not be performed so as perfectly to register two or more punches with a corresponding number of female dies.

One of the objects of this invention is to 90 provide a simple and practicable arrangement whereby groups of dies can be mounted on the same machine and accurately centered, each with its own punch.

Referring now to the drawings, the invention is shown as applied to a die press having the usual die bed 10 secured in position by bolts 11, or in any other desired way. This co-operates with a punch block 12, mounted on a plunger and adapted to reciprocate therewith. This punch block, as shown in the present case, is provided with two die punches 13. Each of these is formed of a desired shape to give the necessary configuration to the interior of the 105 article to be produced. In the present case they are octagonal in form.

The die bed is provided with the same number of recesses 15, adapted to be located directly under the punches. Each re- 110

cess is provided as usual with a passage 16 for receiving the end of the punch. In each of these recesses 15 is placed a die member 17, smaller in size than the recess. Preferably the recess and die member are both circular. For the purpose of accurately centering each of these die members and securing them in adjusted positions, adjusting screws 18 are provided, preferably three in number.

10 Above each die member 17 is a second die member 19 having a central depression 20 for centering it on a projection 21 on the die member 17. This, as will appear, is the reducing die, while the die 17 is the finishing die. The dies 19 are also capable of adjustment for centering purposes and for that purpose and for holding them in position, each one is provided with a reduced neck 22, 20 which sets into a correspondingly shaped hole in a clamping plate 23. These clamping plates are secured to the die bed by bolts 24 passing through holes 25 through these plates. These holes are larger than the bolts 25 to permit of the necessary adjustments.

It is to be noted that each reducing die has a central opening therethrough of circular cross section, flaring out at the top to assist in guiding the cup-shaped blank into 30 position. In this way the operation of the punch in the reducing die is to elongate the blank and reduce its diameter.

The finishing die is provided with a central perforation registering with and, preferably as shown, forming a continuation of the passage through the reducing die. It is flared out at the top to a diameter equal to that of the bottom of the passage in the reducing die. The upper portion of the passage in the reducing die is circular, but it is gradually reduced to the desired polygonal form and retains that form to the bottom. In the form shown, it is of course of the same shape as the punch 18, but of larger size. 45 The difference represents the thickness of the metal of the article to be produced.

In operation, the die bed is fastened in position approximately centrally with respect to the punches. Then a blank that has 50 previously been formed is applied on the end of each punch and then brought down into the dies which are loosely located in the recesses 15. When the articles on the punches enter the smallest portions of the passages in the dies 17, these dies will be centered thereto. Then the screws 18 are tightened up so as to hold them firmly in their central positions. This also results in centering the dies 19. The bolts 24 are then tightened to secure 60 them in their proper places.

The operation of reducing an article is as follows: A flat piece of sheet steel, or other metal, is punched out to the desired circular form. It is then preliminarily operated 65 upon in an ordinary set of dies to form a

shallow cup A. Two of these cups, preferably while cold, are placed by hand on the tops of the two dies 20 and the punches brought down. The first effect of the punching operation is to simultaneously reduce 70 these two cups in the reducing dies and at the same time elongate them. This, according to the old system, would be the end of this step of the operation and the blanks thus reduced would be taken out of the machine and thrown aside to be reheated when 75 ready to go through the next operation. But according to my invention, reheating does not have to be done because I have discovered that the operation of reducing just 80 described imparts enough heat to the blank to permit of its being introduced immediately into the finishing dies and finished, provided it is not allowed to cool off. Consequently, by my procedure, I not only reduce the blank, but with the continuous motion of the punch, I force the heated blank into the finishing die and finish it at the same heat. In this way, no reheating has to be done after the blank is first introduced 85 into the reducing die. It will be seen in this way that by use of two punches, four operations are simultaneously performed, namely two reducing and two finishing operations, where only one reducing or one finishing 90 operation has been practicable heretofore, and furthermore, the delay and expense of the usual reheating between the reducing and finishing operations is entirely eliminated. Even the reheating ovens can be dispensed with in some factories.

Although I have illustrated and described only a single form of the invention and shown it as applied to the manufacture of an article of only one shape, I am aware of the fact that the invention can be carried out in many other forms and applied to many other articles without departing from the scope of the invention as expressed in the claims. Therefore, I do not wish to be 100 limited in these respects, but

What I do claim is:—

1. In a device for producing hollow articles from sheet metal blanks, the combination of a die, a second die located adjacent to and centered with respect to the first die and having a different cross section, and a punch having a cross section similar to that of the second die and movable through the first die directly into the second die.
2. In a device for producing hollow articles from sheet metal blanks, the combination with two dies arranged axially in alignment with each other, both dies having passages therethrough, the passage in the first die being larger than the passage in the second die and of different shape, a punch movable through the passages in both dies, and means connected with the dies for centering them with respect to each other.

3. In a device for producing hollow articles from sheet metal blanks, the combination of a reducing die having a passage therethrough of circular cross section and flared out at the entrance end, and a second die centered with respect to the reducing die and provided with a passage smaller than the passage in the reducing die and of polygonal cross section and flaring out at the surface nearest the reducing die and formed at the surface of substantially the same shape as that of the passage through the reducing die, means coöperating with said dies for centering them with respect to each other, and a punch adapted to pass through the reducing die into the second die and having a cross section similar to the cross section of the passage through the second die.
4. In a device of the character described, the combination of a die bed having a recess in its face, an inner die adapted to be received in said recess and provided with a passage therethrough, an outer die having a passage therethrough larger than the passage in the inner die and centered on said inner die, and means for adjusting the inner die in said recess and securing it in adjusted position.
5. In a device of the character described, the combination of a die bed having a plurality of recesses therein, a plurality of dies arranged in each recess, one die of each set being seated at the bottom of the recess, means for adjusting the last named dies in their respective recesses and securing them in adjusted positions, and a plunger block having a series of punches in fixed position thereon, one for each set of dies.
6. In a device of the character described, the combination of a die bed having a recess in its face, an inner die adapted to be received in said recess and provided with a passage therethrough, an outer die having a passage therethrough and centered on said inner die, means for adjusting the inner die in said recess and securing it in adjusted position, means for clamping the second die in its adjusted position, the last named means being arranged to permit the outer die to move while the inner die is being adjusted, and a punch movable through both dies.
7. In a device of the character described, the combination of a die bed having a plurality of recesses therein, a plurality of dies arranged in each recess, one die of each set
- being seated at the bottom of the recess, means for adjusting the last named dies in their respective recesses and securing them in adjusted positions, a punch block having a series of punches in fixed position thereon, one for each set of dies, a plate for an outer die of each set having means for receiving and holding the outer die, and means for fastening it to the die bed, each of said plates and its fastening means being arranged to move with the inner die while being adjusted.
8. In a device of the character described, the combination of a die bed having a plurality of recesses in its face, finishing dies arranged movably in said recesses, screws in said die bed for adjusting and holding the finishing dies in position in the recesses, a punch block having a series of punches adapted to enter said finishing dies and center the same, a corresponding series of reducing dies, each finishing and reducing die having a central projection and depression fitting each other, by which the reducing dies are centered with respect to the finishing dies, a series of plates having perforations for receiving the reducing dies, and means relatively movable with respect to said plates for clamping them in position after the dies are centered.
9. In a device of the character described, the combination of a die bed, an inner die provided with a passage therethrough, an outer die having a passage therethrough and centered on said inner die, means for adjusting the inner die and securing it in adjusted position, means for clamping the second die in its adjusted position, the last named means being arranged to permit the outer die to move while the inner die is being adjusted, and a punch movable through both dies.
10. The combination of a die bed, a plurality of sets of dies arranged thereon, means for adjusting the dies individually and securing them in adjusted positions, and a plunger block having a series of plungers in fixed position thereon, one for each set of dies.

In testimony whereof I have hereunto set my hand, in the presence of two subscribing witnesses.
